Primary Examiner—Dominic Simone
Attorney, Agent, or Firm—Banner & Witcoff, Ltd.**[57] CLAIM**

The ornamental design for a portion of a shoe upper, as shown and described.

DESCRIPTION

FIG. 1 is a perspective view of a portion of a shoe upper in accordance with a first embodiment of my new design;

FIG. 2 is a side elevational view of the portion of a shoe upper of FIG. 1;

FIG. 3 is a front elevational view of the portion of a shoe upper of FIG. 1;

FIG. 4 is a top plan view of the portion of a shoe upper of FIG. 1;

FIG. 5 is a perspective view of a portion of a shoe upper in accordance with a second embodiment of my new design;

FIG. 6 is a side elevational view of the portion of a shoe upper of FIG. 5;

FIG. 7 is a front elevational view of the portion of a shoe upper of FIG. 5; and,

FIG. 8 is a top plan view of the portion of a shoe upper of FIG. 5.

The uneven broken line showing of the triangular eyelet element, eyelets, lace loops and the remainder of the shoe is for illustration purposes only and forms no part of the claimed design.
